UNITED STATES PATENT OFFICE.

ROBERT HAMILTON IRELAND, OF RICHMOND HILL, NEW YORK, ASSIGNOR OF ONE-HALF TO GEORGE SEAMAN, OF UNION HILL, NEW JERSEY.

GLARE PREVENTER FOR HEADLIGHTS.

Application filed April 7, 1923. Serial No. 630,545.

To all whom it may concern:

Be it known that I, ROBERT H. IRELAND, a citizen of the United States, and a resident of the city of New York, Richmond Hill, 5 borough of Queens, in the county of Queens and State of New York, have invented a new and Improved Glare Preventer for Headlights, of which the following is a full, clear, and exact description.

10 This invention relates to headlights for automobiles and particularly to an improved construction wherein the glare is reduced to a minimum or completely eliminated and has for an object to provide a 15 construction which may be readily applied to headlights now in use.

Another object of the invention is to provide a device capable of ready application to the ordinary headlight now in use and 20 which will permit the light to illuminate the road without producing a glare along side of the road.

A further object, more specifically, is to provide a light deflecting structure for 25 headlights designed to soften the light by causing a diffusion thereof before the light leaves the vicinity of the lamp.

In the accompanying drawing—

Figure 1 is a front view of a complete 30 headlight with a device embodying the invention applied thereto.

Figure 2 is a side view of the lamp shown in Figure 1 with certain parts broken away on line 2—2 of Figure 1.

35 Figure 3 is an enlarged perspective view of the glare preventing device shown in Figure 1.

Referring to the accompanying drawing by numerals, 1 indicates an ordinary headlight provided with the usual reflecting mirror 2 and an electric lamp or bulb 3 adapted to be screwed into a suitable socket 4 in the usual manner. The glare preventing device is shown particularly in Figure 3 in which 45 it will be seen that there is provided a base or bottom ring structure 5 and an outer or top ring structure 6 connected by spaced arms 7 whereby a plurality of apertures 8 are presented. The ring 5 is preferably flat 50 while the ring 6 is bent back upon itself as shown in Figure 2 and forms a substantially S-shaped structure in cross section with an edge 9 adapted to engage the reflecting surface 2. A plurality of projecting tabs 10

are provided to present supporting feet 55 whereby the edge 9 will not injure the reflecting surface 2. The ring 6 is provided with the same number of apertures 11 as there are apertures 8 but the apertures 11 are arranged opposite the arms 7 whereby 60 the rays of light passing from the lamp 3 must pass through the apertures 8, strike part of the reflecting surface 2 and become diffused, after which, the diffused light is permitted to escape through the apertures 65 11 to give the desired illumination of the road. The lamp 3 will, of course, give some direct illumination but no reflected illumination except that which passes through the apertures 11.

70 The device may be secured in the headlight 1 by suitable screws 12 if desired, or other suitable securing means though under most circumstances the lamp 3 extending through the aperture 13 will act as supporting means. The device as illustrated, may be made of any desired kind of metal and is preferably nickel plated on the outside and either gold plated or nickel plated on the inside. It will also be noted from Figure 80 2 of the drawing that the device is beveled or inclined from the top portion downwardly.

What I claim:—

1. A glare preventing device for headlights, comprising an opaque cup-shaped member having apertures in the side walls, and an apertured ring substantially radiating rearwardly from the top of said member, the apertures in the ring and the cup-shaped member being staggered.

2. A device for headlights for preventing glare, comprising a cup-shaped member facing substantially in the direction of the headlight and fitting in the bottom of the headlight, said cup-shaped member having a plurality of spaced apertures in the side walls thereof, and a ring radiating rearwardly from the outer end of said cup-shaped member, said ring having a plurality of apertures positioned in staggered relationship to the apertures of the cup-shaped member, said ring also being formed with a plurality of supporting extensions.

3. A device for preventing glare from headlights, comprising a cup-shaped member fitted into the headlight and surrounding the lamp socket thereof, the lamp of the

headlight being adapted to be positioned in the cup-shaped member, said cup-shaped member being provided with a plurality of apertures in the side walls thereof, and a 5 ring structure extending from said cup-shaped member to the reflecting surface of the lamp, said ring having a plurality of apertures staggered in relation to the first mentioned apertures whereby rays of light from said lamp will become diffused to a 10 certain extent before passing out the last mentioned apertures.

ROBERT HAMILTON IRELAND.
